UNITED STATES PATENT OFFICE

ROY B. GALE, OF FRISCO, COLORADO

CABINET

Application filed May 13, 1931. Serial No. 537,144.

The object of this, my present invention, is the provision of a dispensing cabinet for soft tissue in lavatories, in which the tissue is removed from the cabinet in sheets, each sheet, prior to its removal being treated to an antiseptic deodorant which has medical property and which is delivered only to the under face thereof so that the same will not impregnate the hand of the user when the sheet is removed from the cabinet.

A further object is the provision of a cabinet for this purpose divided into two compartments, one having a liquid antiseptic deodorant therein, the other having rolls, one containing a roll of soft tissue, others providing guides for the roll and one of the last named rolls having a valve to establish a communication with the deodorant container or receptacle to deliver a quantity of deodorant onto the paper that travels over the said roll, together with means of a novel nature for causing the severing of the perforated tissue sheets, so that only the severed sheets delivered from the cabinet will be treated with a deodorant, the said means advancing another sheet to a position for removal after the first severed sheet has been drawn out of the cabinet.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation of the improvement.

Figure 2 is a sectional view approximately on the line 2—2 of Figure 3.

Figure 3 is a vertical longitudinal sectional view through the improvement.

Figure 4 is a sectional view approximately on the line 4—4 of Figure 2.

Figure 5 is a plan view.

Figure 6 is a detail elevation with parts in section to illustrate the brake and feed mechanism.

The cabinet 1 is preferably constructed of metal or of some other water-proof material. The cabinet is of a size to be conveniently hung on the wall of a lavatory next to the toilet seat. The cabinet is divided by a vertical partition 2 into a compartment 3 for the liquid antiseptic deodorant and a compartment 4 for the roll of soft tissue paper and the delivery rolls for the said paper. The tissue 5 is divided into sheets by lines of spaced perforations 6.

The deodorant chamber or compartment 3 has an inlet opening at the top thereof which is normally closed by a screw cap 7 and the partition 2, adjacent to the bottom thereof, is provided with an aperture 8 that affords an outlet port for the liquid deodorant so that the same can flow into the compartment 4. The flow of the liquid is permitted only at determined intervals, the port 8 being closed by a disc 9 which is arranged in the compartment 4 and frictionally contacts with the partition 2. The disc is provided with an aperture 10 which, when brought into register with the port 8, permits of the flow of deodorant into the bottom of the compartment 4 and onto a rubber roll 11 that is fixed on a shaft 12 to which the valve disc 9 is also fixed.

Above the roll 11 there is another roll 13, and the compartment 4, in a line with the contacting peripheries of the rolls 11 and 13, has its face provided with an outlet opening for the sheets of tissue 6. The opening is indicated by the numeral 14 and on the lower wall provided thereby there is an outstanding shelf 15 that affords a guide for the sheets of tissue.

To one side of the roll 13 there is fixed on a suitable shaft 16 (journaled in bearings in the compartment 4) a combined feed and tissue sheet breaking roll 17. The roll 17 is of a less diameter than the rolls 11 and 13.

Above the roll 13 there is removably jour-

naled in suitable bearings the shaft 18 that carries a roll, around which there is wound the soft tissue 5. One of the bearings for the shaft 18 is indicated for distinction by the numeral 19 and is movable through one side of the compartment 4 and the cylindrical body portion thereof is hollow and has arranged therein a spring 20 to contact with one end of the shaft 18 to force the said shaft into the second bearing 21 therefor, the last named bearing being fixed on the partition 2.

On the shaft 16 for the roll 17, at one end of the roll there is fixed a tooth 22 that has an angle side. Fixed on one side of the roll 13 there is a disc-like member 23 provided with diametrically opposite teeth 24, respectively. Journaled for free movement on the shaft 25 for the said disc 13 there is an arm 26, and pivoted on this arm there is a dog 27 that is designed to engage with either of the teeth 24. The arm 26 has an offset handle portion 28 received through a semi-circular slot 29 in the outer side of the compartment 4. On the end of the arm 26 journaled on the shaft 25 there is secured or formed a finger hold 30. The arm 26 is influenced by a spring 31 to bring the handle 28 against the outer end wall provided by the semi-circular slot 29.

The top of the compartment 4 is open or has an opening therethrough which is closed by a flanged cover 32, and whereby access to the compartment 4 may be obtained to arrange a fresh roll of tissue therein or to arrange the shafts of the rolls in the bearings therefor.

In operation the sheets of tissue are guided between the rolls 13 and 17 and over the roll 11 which is a feed roll for the antiseptic deodorant. The handle 28 when swung through the slot 29 will impart a turning movement to the roll 13 and a like movement to the roll 17 which frictionally engages with the roll 13. However, when the handle 28 is swung to the center of the slot 29, or is given one-fourth of a turn the dog 27, engaging with one of the teeth 24 on the member 23 will swing the finger 30 to cause the same to contact with the tooth 22 to stop the movement of the tissue between these rolls to permit of the sheet of tissue arranged between the rolls 11 and 13 being severed from the remainder of the tissue roll. Thus the roll 17 is in the nature of a breaker for the sheets of tissue. The finger only momentarily engages with the tooth 22, the further swinging of the handle 28 causing the finger to ride off of the said tooth and thus permitting both of the rolls 13 and 17 to turn and by virtue of such turning to bring the end sheet of tissue in a position to be received between the rolls 11 and 13. The spring 31 returns the handle and the finger 30 to initial positions, which are indicated by the dotted lines in Figure 2

of the drawings and in the full lines in Figure 6. The sheet of paper received through the opening 14 and arranged between the rolls 11 and 13 will have its under face treated with a deodorant but the top of the sheet may be grasped by the operator without contact with the bottom face of the said sheet and thus without impregnating his fingers with the deodorant.

My invention, it will be seen, provides a more sanitary means of cleansing after bowel movement than mere toilet paper will give.

The sanitary tissue is treated with a deodorant that is antiseptic, soothing and healing, regardless of its frequent use. The healing purpose of the deodorant is for those afflicted with hemorrhoids, leaving a feeling of cleanliness that toilet paper cannot possibly do. A deodorant that will readily absorb itself in a tissue similar to that of "Kotex". The deodorant has a very peculiar cleansing effect. The tissue should be somewhat larger than toilet paper and of a thickness adequate to adsorbing a sufficient amount of the deodorant for practical use. Toilet paper could, of course, be used first, then two or three sheets of deodorized tissue. The use of the toilet paper is not really necessary, merely use more of the deodorized tissue. The tissue remains dry and untreated until it is pulled from the container. The deodorant is evenly spread upon it, upon the bottom side. The top of the tissue is dry where the hand comes in contact with it.

The roll 13, it will be noted, is in the nature of a feed roll, the roll 17 is in the nature of a presser and stop roll while the roll 11 constitutes the deodorant feed roll as well as a guide roll for the detached sheet of gauze-like tissue. All of the rolls are in frictional contact with each other.

Having described the invention, I claim:

1. A cabinet divided into two compartments, one containing a deodorant and said compartment having an opening communicating with the second compartment, the second compartment having a roll of soft tissue journaled therein, perforated to divide the same into sheets, rolls between which the sheets are directed, another roll journaled in the cabinet in contact with one of the first named rolls, an apertured disc providing a valve mounted with the last named roll for admitting the deodorant into the second named compartment when the aperture in the disc registers with the opening in the deodorant compartment, means on the shaft of one of the first named rolls for turning the latter to unroll the tissue, means operated by said turning means for momentarily stopping one of the contacting rolls to cause the severance of the sheets of tissue and for directing the sheets singly through the cabinet to cause the roll provided with the valve to contact

with the under face of the sheet to impregnate the same with the deodorant.

2. A cabinet for delivering sheets from a roll of tissue and for treating the said sheets prior to delivery with a deodorant, comprising a feed roll, a presser roll in frictional contact therewith, a deodorant applying roll in frictional contact with the feed roll, the feed roll and the presser roll designed to receive therebetween undetached tissue from the tissue roll, means for revolving the feed roll for approximately one-half of its circumference, means operated by the feed roll when the same has been turned approximately one-fourth of its circumference for stopping the rotation of the presser roll to cause a sheet to be severed from the gauze and means releasing the presser roll on the further turning of the feed roll to cause the severed sheet to be delivered between the feed roll and the deodorant applying roll partially through the cabinet.

3. A cabinet for the purpose set forth, divided into a deodorant compartment and into a roll compartment, said last named compartment having arranged therein a roll of gauze tissue, a feed roll for the tissue, a presser roll which contacts with the feed roll and a deodorant applying roll which also contacts with the feed roll, means for turning the feed roll approximately one-half of a revolution, means actuated by the feed roll when the same has been turned approximately one-fourth of a revolution for stopping the turning of the presser roll to permit of a sheet of gauze tissue being severed from the remainder of the tissue, means actuated on the further turning of the roll for delivering the tissue between the feed roll and the deodorant applying roll, means actuated by the turning of the deodorant applying roll for admitting a determined quantity of deodorant from the deodorant compartment into the roll compartment upon the deodorant applying roll and means for returning the presser roll stopping means to initial position without influencing the turning of the feed roll.

4. A cabinet for the purpose set forth, divided into a deodorant compartment and into a roll receiving compartment, which latter compartment is provided with an opening, a roll of gauze tissue removably secured in the roll compartment, a feed roll for the tissue, a presser roll in frictional contact with the tissue and with the feed roll, a deodorant applying roll in frictional contact with the feed roll, a lug on the shaft for the feed roll, cam members fixed on the shaft for the presser roll, a cam on the shaft for the feed roll, ratchet teeth on the shaft of the feed roll, an arm journaled on said shaft and having dogs to engage with the ratchet, a finger carried by the arm, an operating handle for the arm movable through a semi-circular slot in one

side of the cabinet, said finger, when the arm is operated to turn the feed roll approximately one-fourth of a revolution, designed to contact with the dog or to stop the presser roll and to permit of the severance of a sheet from the gauze tissue and upon the further turning of the feed roll to cause the finger to move off of the dog of the feed roll to permit of the further turning of the feed roll and the presser roll to deliver the severed sheet between the feed roll and the deodorant applying roll and partially through the opening in the cabinet, spring means for returning the arm to initial position without influencing the turning of the feed roll and means operated by the turning of the deodorant applying roll for admitting deodorant from the deodorant chamber onto said roll.

In testimony whereof I affix my signature.

ROY B. GALE.
